US0D1069400S

(12) United States Design Patent (10) Patent No.: US D1,069,400 S
(45) Date of Patent: * Apr. 8, 2025

(54) HANDBAG

(71) Applicant: ODM GmbH, Wattenheim (DE)

(72) Inventor: Christopher Kühn, Obrigheim (DE)

() Term: 15 Years

(21) Appl. No.: 35/516,371

(22) Filed: Jan. 24, 2023

(80) Hague Agreement Data

Int. Filing Date: Jan. 24, 2023

Int. Reg. No.: DM/226809

Int. Reg. Date: Jan. 24, 2023

Int. Reg. Pub. Date: Feb. 24, 2023

(30) Foreign Application Priority Data

Sep. 5, 2022 (DE) 40 2022 100 659.4

(51) LOC (15) Cl. 03-01

(52) U.S. Cl.

USPC D3/246; D3/203.1; D3/217

(58) Field of Classification Search

(57) CLAIM

The ornamental design for a handbag as shown and described.

DESCRIPTION

1. Handbag
2. Handbag
3. Handbag
- 1.1: Top
- 1.2: Back
- 1.3: Left
- 1.4: Right
- 1.5: Front
- 2.1: Top
- 2.2: Back
- 2.3: Left
- 2.4: Right
- 2.5: Front

3.1 Top
3.2 Back
3.3 Left
3.4 Right
3.5 Front
